UNITED STATES PATENT OFFICE

113,359

DESIGN FOR A NAIL FILE

Paul J. Carpenter, Newark, N. J.

Application August 18, 1938, Serial No. 79,422

Term of patent 14 years

To all whom it may concern:

Be it known that I, Paul J. Carpenter, a citizen of the United States and a resident of Newark, in the county of Essex and State of New Jersey, have invented a new, original, and ornamental Design for a Nail File, of which the following is a specification, reference being had to the accompanying drawing, forming part thereof.

Figure 1 is a front elevational view of the nail file, and

Figure 2 is a side view of Figure 1.
The dominant features of my design reside in the portions shown in full lines.

I claim:
The ornamental design for a nail file, as shown and described.

PAUL J. CARPENTER.
